UNITED STATES PATENT OFFICE.

LOUIS B. PRAHAR, OF BROOKLYN, NEW YORK.

TABLET ATTACHMENT FOR THE FRAMES OF PURSES.

SPECIFICATION forming part of Letters Patent No. 430,351, dated June 17, 1890.

Application filed January 18, 1890. Serial No. 337,384. (No model.)

To all whom it may concern:

Be it known that I, LOUIS B. PRAHAR, of Brooklyn, in the county of Kings and State of New York, have invented a new and useful 5 Tablet Attachment for the Frames of Purses, &c., of which the following is a full, clear, and exact description.

My invention relates to a tablet attachment for the frames of purses, chatelaine 10 bags, and other analogous articles, and has for its object to provide a means whereby one or more leaves or tablets may be made to constitute virtually a portion of the frame, or be attached thereto, which leaves or tabs- 15 lets will be convenient of access and may be concealed when not in use.

The invention consists in the novel construction and combination of the several parts, as will be hereinafter fully set forth, 20 and pointed out in the claims.

Reference is to be had to the accompanying drawings, forming a part of this specification, in which similar figures of reference indicate corresponding parts in all the views.

25 Figure 1 is a perspective view of a purse having the invention applied thereto, the tablets being concealed; and Fig. 2 is a plan view of the purse with the tablets disclosed.

It is the prime object of the invention to 30 obviate the necessity of carrying shopping-tablets loosely in a purse or bag or in the pocket, and to so construct the frame of a purse or bag that one or more tablets adapted to receive memoranda may be rendered visi-

35 ble when required for use or reference and concealed when not so needed, thus adding to the utility of the article to which they are attached, and also avoiding the inconveniences often experienced by shoppers—namely, 40 their inability to readily find the tablet among the many articles contained in the pocket or bag and the liability to forget or to readily lose such tablet.

In the drawings I have illustrated the in- 45 vention as applied to the flat frame of a purse, the said frame consisting of a ring 10, to which the body of the purse is secured, a cover-plate 11, hinged to the said frame and

provided with any approved form of catch, and an auxiliary cover-plate 12, pivoted upon 50 the main cover-plate 11 in such manner that it may be swung laterally upon the main cover-plate to disclose the same, as best illustrated in Fig. 2.

The tablets 13 are in this instance cut to 55 correspond with the contour of the main cover-plate, which is provided with a depression 14 in its upper face to receive them; or instead the depression may be formed in the under surface of the auxiliary cover-plate. 60

The tablets 13 may be made of any suitable material capable of being written upon by a slate or by a lead pencil, and having the surface so prepared that the marks may be erased, the preferred material employed be- 65 ing something similar to silicate, celluloid, or zylonite.

The tablets may be attached to the frame in many ways, the mode of attachment illus- 70 trated consisting in pivoting the leaves be- between the auxiliary and main cover plates upon the pivotal pin of the former; but I de- 75 sire it to be distinctly understood that I do not confine myself to this mode of applying the tablets, as they may be secured in any approved manner to the under face of the main cover-plate or to any portion of a bag or 80 purse frame best adapted to receive and conceal them.

Having thus described my invention, I claim 80 as new and desire to secure by Letters Patent—

1. As an improved article of manufacture, a purse, pocket-book, or bag frame having one member thereof provided with a series of 85 hinged memoranda-tablets and with a hinged cover for the said tablets, as specified.

2. As an improved article of manufacture, a purse-frame having a hinged cover provided with a series of tablets hinged thereto and 90 with a hinged cover for the tablets, as set forth.

LOUIS B. PRAHAR.
